DISPENSING DEVICE

Earl R. Carper, San Francisco, Calif.

Application October 19, 1953, Serial No. 386,823

7 Claims. (Cl. 221—56)

This invention relates to dispensing devices and more particularly to a device for dispensing disposable paper sheets and the like.

The main object of the invention is the provision of a device for holding a stack of folded paper sheets and having incorporated therein means for wetting the sheets with a liquid so as to facilitate the cleansing operation.

Another object of the invention is the provision of a compact device adapted to contain a stack of paper sheets and a reservoir for fluid, with said stack and reservoir being arranged in such a manner as to facilitate the use of such sheets for whatever purpose desired.

Still another object of the invention is the provision of a combination paper compartment and wetting device which is inexpensive to make and foolproof in operation.

Other objects and advantages will be seen in the following specification and drawings:

Fig. 1 is a front elevational view of the invention.

Fig. 2 is a vertical cross sectional view through the device as taken along lines 2—2 of Fig. 1 and showing the individual sheets of paper schematically by means of single lines.

Fig. 3 is an enlarged fragmentary cross sectional view of the device adjacent the discharge neck of the fluid reservoir.

Fig. 4 is an end elevational view partly broken away and in section showing the manner of operation.

Fig. 5 is a reduced front elevational view of a modified form of the invention having two fluid reservoirs.

In detail, the invention comprises a compartment or box generally designated 1 which may be made of any suitable material such as cardboard or plastic. The box 1 is preferably rectangular and comprises a top wall 2, a bottom wall 3, opposite front and rear walls 4, 5 and opposite end walls 6, 7.

Compartment 1 is adapted to receive therein a stack of paper sheets 10 (Fig. 2) of any desired consistency. Preferably each sheet 10 is folded to provide a vertically extending major portion 11 and a half fold 12 which is folded upon itself to provide a relatively narrow front fold 13 which is positioned about centrally of the vertical extent of the folded sheet. Preferably the major portion 11 terminates at its upper end in a relatively narrow marginal fold 14.

When a plurality of sheets 10 are stacked within the compartment 1 as above described, and as shown in Fig. 2, it will be seen that the flap 13 of the sheet adjacent front wall 4 may be grasped by the fingers of the user through an opening 15 in the front wall 4.

Opening 15 is preferably formed by providing a generally U-shaped portion 17 (Fig. 1) in front wall 4 defined by a pair of rows 18, 19 of perforations or other means for establishing lines of weakness. By removing the portion 17 in the manner indicated in Fig. 1, it is seen that a flap 20 is formed which is hingedly secured along a line 21 (Fig. 1) to the front wall 4. If the compartment 1 is made of plastic instead of cardboard, a hinge may be

2

provided to swingably secure the flap 20 to the front wall 4.

Between the inner end of the stack of sheets 10 and the rear wall 5, is positioned a hollow bulb or reservoir 25 which may be formed of rubber or the like. This bulb 25 is provided with a reduced neck portion 26 (Fig. 3) which is formed with an internal annular projection 27 adapted to be received in a complementarily formed annular groove 28 in a closure or stopper 29. By this structure it is seen that the stopper 29 is firmly but removably secured within the neck 26 of the bulb 25 and effects a tight seal.

The bulb 25 flares outwardly and upwardly from neck 26 as seen in Fig. 3 and is provided with a pair of spaced lips 30, 31. The top wall 2 is provided with a hole 32 adjacent to but spaced from rear wall 5 and the annular marginal portion 33 of top wall 2 which surrounds hole 32 is received between said lips 30, 31 as seen in Fig. 3. Inasmuch as both the marginal portion 33 and the lips 30, 31 are yieldable, it is a simple matter to affix the bulb 25 so that it depends from said top wall 2.

A hanger strip 35 is carried by the upper end of bulb 25 and may be integral therewith. At one end of said strip 35 the same is provided with an aperture 37 by means of which the entire assembly may be suspended from a hook or nail. Preferably a conventional suction cup 39 is integrally carried by said strip to permit attachment to an automobile window, dash board, or firewall, or to permit the device to be fastened to a bathroom wall, mirror or other smooth surface.

Extending axially through the closure 29 is a rigid conduit 40 which terminates at its lower end adjacent the bottom of bulb 25. Conduit 40 projects outwardly a short distance from closure 29 so as to receive one end of a relatively short flexible discharge tube 42 which is precured to extend over the top 2 and terminates at its end opposite conduit 40 in a downwardly directed discharge portion for directing liquid downwardly in a stream alongside but spaced outwardly from front wall 4.

In operation, the closure 29 is removed from bulb 25 so that the latter remains suspended from top wall 2. The bulb may thus be filled with water or any other liquid and the closure replaced with the discharge tube 42 directed forwardly as shown in Fig. 4. The assembly may then be attached to any desired support, although it will be noted that once it is attached it is not necessary to remove it to fill bulb 25 unless the same is in an inaccessible position.

The user may then remove the paper sheet that is adjacent front wall 4 by lifting up slightly on front flap 20 of compartment 1. It will be noted that the front fold 13 of each sheet 10 is immediately accessible to the user although protected from dirt and grime at all times by flap 20 when the front sheet is removed. The next sheet is always immediately available for subsequent use because of the manner of folding the sheets as above described.

After a sheet is removed it may be retained in the same hand and the front flap 20 may then be pressed inwardly by the index finger or thumb of the user so as to compress bulb 25 and force the liquid contained therein through discharge tube 42 onto the sheet 10. For most purposes, such as cleaning a window or spotting a soiled surface, a very small amount of water is all that is required.

By the above described structure it will be seen that practically no more time is required to make available a wetted sheet of paper than to withdraw a dry sheet from a conventional dispenser.

An extremely important feature of the invention resides in the cooperation between the bulb 25 and the sheets 10, together with the walls of the compartment 1.

In this connection it will be noted that the bulb 25 is always at least slightly compressed at all times so that it cooperates with the sheets 10 to urge the latter against front wall 4 where they are immediately available at all times for removal through opening 15. Furthermore, the sheets 10 cooperate with the flap 20 to compress the bulb 25 when it is desired to discharge fluid from the latter.

Although it is usually desirable to have a full charge of paper in compartment 1 when the bulb 25 is being refilled, the discharge tube 42 is formed from rubber or the like to make the same flexible to permit the user to pinch it while new sheets of paper are being inserted. By this structure any inadvertent leakage is obviated.

The present invention is not limited to use with water for cleaning purposes and it will be understood that the bulb 25 may be filled with any desired liquid such as germicides, insecticides, solvents, oils, perfumes and pharmaceutical liquids depending upon the particular use to which it is to be put.

More than one reservoir may be employed for different liquids as desired. Thus, in Fig. 5 there is shown a compartment 50 provided with two bulbs to which are connected discharge tubes 51, 52 respectively. This particular modification is especially desirable for use with cosmetics when the successive use of two or more liquids is desired.

Although the invention has been described for use with paper sheet it will be understood that other folded material, such as cloth or gauze sheets may be employed.

The specific embodiments of the invention described should not be understood as limitations of the invention as it is obvious that various modifications in design may be made without departing from the following claims.

I claim:

1. A dispenser for paper and the like, comprising a compartment containing a charge of sheets and having an opening in one side through which such sheets may be removed, a resilient reservoir for fluid in said compartment adjacent the side opposite said one side and adapted to be compressed by movement of said charge toward the same, said reservoir being provided with an outlet externally of said compartment whereby pressure applied to said one side is transferred through said charge compresses said reservoir and forces said fluid through said outlet.

2. A dispenser for paper and the like, comprising a compartment containing a charge of sheets and having an opening in one side through which such sheets may be removed, a resilient reservoir for fluid in said compartment adjacent the side opposite said one side and adapted to be compressed by movement of said charge toward the same, said reservoir being provided with an outlet externally of said compartment whereby pressure applied to said one side is transferred through said charge compresses said reservoir and forces said fluid through said outlet, said outlet being positioned so as to discharge such fluid outwardly of said one side.

3. A dispenser for paper and the like, comprising a compartment containing a charge of sheets and having an opening in one side through which such sheets may be removed, a resilient reservoir for fluid in said compartment adjacent the side opposite said one side and adapted to be compressed by movement of said charge toward the same, said reservoir being provided with an outlet externally of said compartment whereby pressure applied to said one side is transferred through said charge compresses said reservoir and forces said fluid through said outlet, a support for said compartment adjacent said opposite side for attaching said compartment to a wall, whereby said pressure is resisted by the latter when said compartment is resisted by the latter when said compartment is so attached.

4. A dispenser for paper and the like, comprising a

compartment containing a charge of sheets and having an opening in one side through which such sheets may be removed, a resilient reservoir for fluid in said compartment adjacent the side opposite said one side and adapted to be compressed by movement of said charge toward the same, said reservoir being provided with an outlet externally of said compartment whereby pressure applied to said one side is transferred through said charge compresses said reservoir and forces said fluid through said outlet, said one side being provided with a hinged flap overlying said opening to permit compressing said stack by applying pressure on said flap, thereby compressing said reservoir.

5. A dispenser for disposable paper sheets comprising a compartment having a top, bottom, and opposite front and rear walls, said front wall being provided with an opening and a hinged flap covering said opening, a resilient reservoir for fluid in said compartment adjacent said rear wall and depending from said top wall, a charge of paper positioned between said reservoir and said front wall whereby said reservoir compresses said charge and urges the same against said front wall, a flexible self-sustaining discharge tube secured at one end to said reservoir and communicating with the interior of the latter and extending over said top and terminating at its opposite end adjacent said front wall for discharging fluid from said reservoir upon compression of the latter.

6. A dispenser for disposable paper sheets comprising a compartment having a top, bottom and opposite front and rear walls, said front wall being provided with an opening and a hinged flap covering said opening, a resilient reservoir for fluid in said compartment adjacent said rear wall and depending from said top wall, a charge of paper positioned between said reservoir and said front wall whereby said reservoir compresses said charge and urges the same against said front wall, a flexible self-sustaining discharge tube secured at one end to said reservoir and communicating with the interior of the latter and extending over said top and terminating at its opposite end adjacent said front wall for discharging fluid from said reservoir upon compression of the latter, said reservoir comprising a bulb having a discharge neck projecting through said top wall, means securing said neck to said top wall, a removable closure for sealing said discharge neck and a conduit carried by said closure and extending downwardly into said bulb.

7. A dispenser for disposable paper sheets comprising a compartment having a top, bottom and opposite front and rear walls, said front wall being provided with an opening and a hinged flap covering said opening, a resilient reservoir for fluid in said compartment adjacent said rear wall and depending from said top wall, a charge of paper positioned between said reservoir and said front wall whereby said reservoir compresses said charge and urges the same against said front wall, a flexible self-sustaining discharge tube secured at one end to said reservoir and communicating with the interior of the latter and extending over said top and terminating at its opposite end adjacent said front wall for discharging fluid from said reservoir upon compression of the latter, said reservoir comprising a bulb having a discharge neck projecting through said top wall, means securing said neck to said top wall, a removable closure for sealing said discharge neck and a conduit carried by said closure and extending downwardly into said bulb, said flexible discharge tube being secured to said conduit at the upper end of the latter.
